Frank McLaughlin
By his Attorney
J. Steel Jackson.

UNITED STATES PATENT OFFICE.

FRANK McLAUGHLIN, OF PHILADELPHIA, PENNSYLVANIA.

LATHER-BRUSH FOR POWDERED SOAP.

1,354,053.

Specification of Letters Patent. Patented Sept. 28, 1920.

Application filed September 5, 1919. Serial No. 321,950.

To all whom it may concern:

Be it known that I, FRANK McLAUGHLIN, a citizen of the United States, residing at 2325 N. 33rd street, Philadelphia, in the 5 county of Philadelphia and State of Pennsylvania, have invented a certain new and useful Lather-Brush for Powdered Soap, of which the following is a specification.

My invention relates to lather brushes 10 which are intended for use preparatory to shaving.

The purpose of this invention is to provide a narrow opening extending deeply into the brush which will receive and to some 15 extent act as a measure for the quantity of soap powder which it is intended to use and from which the soap will not spill readily but will be distributed throughout the brush.

20 A further purpose is to provide a brush and receptacle handle with coacting retaining parts within the receptacle and with quick and handy release mechanism therefor capable of operation by the hand holding 25 the receptacle handle.

A further purpose is to secure the brush in position by a catch and provide laterally movable release operating mechanism, convenient for use by the hand holding the 30 receptacle handle.

A further purpose is to provide a brush and soap-powder-holding receptacle-handle having a large front opening normally closed by a removable brush, which handle 35 is readily cleaned and which is substantially free from lodging places for dirt and vermin.

40 A further purpose is to provide for quick drying and ready cleansing of a lather brush.

Further purposes will appear in the specification and in the claims.

It has been thought best to illustrate this invention by several different forms of 45 brush-holding mechanism characterized by snap or latch holding devices within the receptacle handle and all but one by lateral movement of the finger contacts of the release mechanism; though it is recognized 50 that other forms of operation will come within the broader claims of this application, and that many other modifications securing lateral movement of the finger contacts will be suggested to the designer by 55 the forms shown. The selected forms have been chosen from a large number because

they are practical, efficient and inexpensive and at the same time well illustrate the principles of the invention.

Figure 1 is a longitudinal central section 60 of one form of the invention.

Fig. 1^a is a longitudinal section showing modified brush holding structure.

Figs. 2, 3 and 4 are sections of Fig. 1 on lines 2—2, 3—3, and 4—4, respectively. 65

Fig. 5 is a perspective view of a sleeve shown in Fig. 1.

Fig. 6 is a section corresponding to line 6, 6, Fig. 1, of the same sleeve, showing the parts in perspective. 70

Figs. 7—10 are perspectives of parts entering into the same brush shown in Fig. 1.

Fig. 11 is a perspective of the catch and related parts of a second form of the invention. 75

Figs. 12, 13, 15, 17 and 18 are longitudinal sections showing other forms.

Fig. 14 is a section upon line 15—15 in Fig. 13.

Fig. 16 is a section upon line 17—17 in 80 Fig. 15.

Fig. 16^a, 17^a is a broken perspective of the end of the receptacle-handle illustrated in Figs. 15 and 16.

Fig. 16^b is a corresponding perspective of 85 the brush base.

Comparatively little difficulty has been met in adapting brushes and brush handles for the use of a fluid or plastic soap, but their weight is against them and it has been 90 found difficult to clean them properly without unduly wasting the reserve supply of soap. However, quick, easy, convenient and cleanly application of a powdered soap to handle container and removable brush use 95 have presented greater difficulty but are attained in the various forms disclosed herein.

Taking up first the form shown in Figs. 1—11:

I provide the brush 20 with a hollow center as shown at 21 extending clear to the base of the brush to give access for cleaning the brush and light and air for drying it and keeping it clean. The opening may conveniently be made of such size as to hold 100 a reasonable charge or quantity for the lather required for a shave.

The open center protects against vermin which seek the dark, damp parts of the brush and fatten on the soap which too 110 often lodges there.

The bristles are held in the annular groove

between the sides 22, 23 of a holder 24, closed at the center at 25 and flanged at 26, to close the open end of the container handle 27.

5 Whether the interior wall 22 of the bristle-holding brush socket shall be straight, as in Fig. 1, or must be tapered, as 24' in Fig. 1^a to give the center opening will depend upon the character of bristles used. The 10 method of retention also will vary, some being set in rubber; some clamped, as between the inner flange 24' and an edge, such as 28 upon the outer flange, etc.

Upon the interior of the brush holder is 15 secured a plug 29, terminating in a ball or other projection 30. It may be held frictionally or sweated in (as in Fig. 1); or may be provided with projections 31', limiting its movement and retained by a screw 32 (as 20 in Fig. 1^a); or by any other suitable means. In the form of Fig. 1^a the head may be tapered to spread or to assist in spreading the inner flange, to spread the bristles more at 21.

25 At the rear end, the container handle is terminated by a base flange 34 upon which the brush is adapted to stand, and is sealed by a closure 35. This is held in position by one or more bayonet joints 35'.

30 Where the base of the brush and the socket into which it fits in the open end of the handle, are cylindrical, it is quite desirable that the sides do not come into contact throughout much of the circumference because of sticking from the soap powder. I 35 therefore prefer to have ribs 33 of contact only, as in Figs. 4 and 7 and may use the ribs also in the tapered forms. The keyed forms are all preferably tapered.

40 The mechanism for retaining the brush parts within the container-handle comprises primarily a tubular sleeve support 36 flanged at 37 after it is in place, to retain it within the handle, spring-pressed retaining mechanism and provision for releasing the retaining mechanism.

45 The support 36 is circumferentially cut at 38 and the cut parts are turned inwardly in the form of ears 39, which are apertured 50 at 40 to receive lateral pivotal projections 41 upon gripping arms 42. These are provided with fingers 43 at their forward ends for engagement with and retention of the ball 30, and with apertures 44 at the reverse ends 55 to pass a rod 45.

The rod carries a spacing compression spring 46 tending to separate the ends 47 of these fingers, and tubular finger-pressed plungers 48 whose ends 48^a are intended to engage with the outer surfaces of the ends of the gripping arms.

60 The space within the receptacle is filled with powdered soap and each time that the brush is set down upon the base 34, this

soap is settled to the rear of the container 65 handle.

In operation:—The brush is moistened and its handle is held in one hand, say the right hand with the forefinger and thumb 70 engaging and pressing the ends of the finger contact members 48. This releases the catches from the ball 30. At the same time the brush end, now free, is withdrawn by the left hand from its seat in the end of the handle and is turned until the bristles extend in an upward direction. A quantity of soap powder is then poured from the container handle, filling the opening in the brush. With the open end of the receptacle 75 directed upwardly, the brush is now inserted in position and is put into place, as in Fig. 1, the finger-pressed members 48 being pushed together to open the catches, while the brush is inserted. The brush is then ready to be applied in producing a lather.

80 In the form shown in Fig. 11 the parts are similar except for the supporting sleeve and the catch mechanism by which the ball terminal of the brush is held.

85 The pivoted catch parts are supported upon a frame 49 instead of upon arms inwardly projected from the sleeve 36. The catch members 42' are provided with apertured pivotal ears 50 bent in from the sides and with cupped terminals at 51, gripping 90 the ball. The spring 46' surrounds the pin 45 and is of torsional form with the same effect, in that it opposes release of the catch members when the finger contacts 48' are 95 pressed.

100 In the form shown in Fig. 12 the sleeve 36' supports leaf springs 52 embodying the functions of the arms and the springs and whose ends 53 spring outwardly into an inwardly-directed flange 54 carried by the base of the brush member. The spring catches are released by laterally (radially) movable pins 55 secured to the springs at one end and carrying heads 56 at the other.

105 In the form shown in Figs. 13 and 14, the rear end of the sleeve 36' supports a transverse strip 57, which may be integral with it as shown, and from whose edges ears 58 are turned. Pins 59 in these ears form 110 pintles for the arms 42' pressed apart by spring 46^a so that their ends 53 engage an inwardly turned flange 54.

115 In the form shown in Figs. 15, 16 and 16^a, the finger contacts 48' terminate at their inner ends in annular, reversely-turned 120 cups 60, whose hubs 61 extend radially for engagement by the fingers. The hubs are bored to receive a pin 62 about which springs 46^b fits, and are counterbored at 63 for screws 64, fitting into the pin and 125 against the hub. Each of the cups engages with an inwardly-turned prong 54' and can be released from it by pressing the finger

contacts toward each other as in the other figures.

Because the fastening device requires that the brush be placed in a particular position, 5 to bring the prongs in line with the cups, the brush base and receptacle seat therefor at the end of the holder are keyed, as shown at 65 in Figs. 16 and 16a.

In the form shown in Fig. 18, the clamping devices or catches 52', are formed of 10 spring material and are terminated by flanges 66, such that by pressure the ball can be forced between them and they will snap over it. The ball can also be pulled out 15 from between them when it is desired to withdraw the brush.

In the form shown in Fig. 18, a single finger contact 67 is apertured to slide upon a pin 45' against compression spring 46'. 20 It carries a prong 43' to pass through an opening in a strip 29' secured to the back of the brush.

In either case the finger contact is flattened and is guided against turning by the 25 walls of the container through which it passes.

In the prong form the back of the brush and the container are keyed to present the 30 opening in the strip. The prong is tapered to tighten the brush within the handle.

It will be evident that the catch or fastener is protected within the container in all of the forms and lies back of the zone of engagement of the brush base with the 35 mouth of the container, so that any tilting pressure against the brush or brush base will be resisted by the catch acting through the leverage which this rearward position of the catch provides.

40 Having thus described my invention, what I claim as new and desire to secure by Letters Patent is:

1. In a lather brush, a brush body having a hollow center of small diameter as compared with the base and extending from the 45 point of the bristles to the base thereof to form an orifice adapted to receive powder, and a handle for the brush.

2. In a lather brush, a brush body having 50 a base, a hollow handle having a wide opening at one end forming a seat for the brush base, a spring-operated catch in the handle and finger contacts connected with the catch and movable laterally of the handle, for releasing the spring catch.

3. In a lather brush, a brush body having 55 a base and having a portion forming a ball projecting engaging shoulder to the rear of the base in combination with a handle and a spring catch within the handle and normally engaging the shoulder.

4. In a lather brush, a brush body having 60 a projection at the rear end thereof, in combination with a separable handle therefor, a spring-operated catch within the handle

adapted to grip the projection and laterally-movable finger contact means to release the catch, said means projecting from the side of the handle.

5. In a lather brush, a brush body, a separable handle therefor and means for releasing the brush from the handle, including finger contacts movable laterally with respect to the handle. 70

6. A round container brush handle, having 75 an open front end for pouring the contents therefrom, in combination with a brush body adapted to project into the front of the handle and catch mechanism back of the body for retaining the handle in position, and radially movable means with respect to the brush handle for operating the catch mechanism.

7. In a lather brush, a hollow handle, a sleeve therein, spring catch mechanism supported by the sleeve and within the handle, a brush body insertible within the handle and a projection upon the brush body engaged by the spring catch mechanism. 85

8. In a lather brush, a hollow brush 90 handle, a member supported therein forming opposing bearing portions to provide supports, spring-pressed catch finger means supported from said bearing portions, normally in closed position, means for releasing the spring-catch finger means, movable radially with respect to the handle and projecting laterally therefrom and a brush body adapted to be engaged by the spring fingers. 95

9. In a lather brush, a hollow receptacle handle, having a base at the rear end and open at the end toward the brush, a brush body adapted to close the open end thereof and having projections at the back and 105 spring-operated catch mechanism for engaging the projections to retain the brush.

10. In a lather brush, a receptacle handle having an open end and an otherwise closed surface, a removable brush having a recess 110 adapted to act as a receiver of the body content and spring-operated holding mechanism within the handle for holding the brush to the body.

11. In a lather brush, a receptacle handle 115 having an open end and an otherwise closed surface, a removable brush and spring-operated holding mechanism within the handle for holding the brush to the body.

12. In a lather brush, a receptacle handle 120 having an open end and an otherwise closed surface, a removable brush and spring-operated holding mechanism within the handle for holding the brush to the body and means for releasing the spring-catch 125 mechanism, movable radially with respect to the brush body.

13. A round container brush handle, having 130 an open front end for pouring the contents therefrom, in combination with a

brush body adapted to project into the front of the handle and spring pressed catch mechanism back of the body for retaining the handle in position.

5. 14. In a lather brush, a handle having an open upper end, a brush body having a brush base smaller in diameter than the open upper end of the handle, spacing means for centering the brush base within the open upper end of the handle clear of the walls thereof, and an annular flange extending from the brush base over the outer edge of the open upper end of the handle.

10 15. In a lather brush, a brush body, a handle having an open upper end, the brush

body having a base having ribs spaced apart and extending longitudinally of the base and adapted to bear against the walls of the open upper end of the handle, and a flange extending from the base over the 20 outer edge of the open upper end of the handle.

16. In a lather brush, a brush body, a brush base, a hollow handle having an open upper end and having rigid walls adapted to receive the brush base, and coacting means in the center of the brush base and handle adapted to interlock as the brush base is thrust into the handle.

FRANK McLAUGHLIN.
